Specification for Design.

Patented May 10, 1921.

Application filed August 16, 1920. Serial No. 403,966. Term of patent 14 years.

To all whom it may concern:

Be it known that I, JOHN H. LICKERT, a citizen of the United States, residing at Evanston, in the county of Cook and State of Illinois, have invented a new, original, and ornamental Design for a Stirring and Turning Tool, of which the following is a specification, reference being had to the accompanying drawing, forming a part thereof.

Figure 1 is a plan view of a stirring and turning tool showing my new design. Fig. 2 is a side elevation thereof. Fig. 3 is a cross section on line A—A of Fig. 2.

I claim:

The ornamental design for a stirring and turning tool, as shown.

JOHN H. LICKERT.
